GEORGE S. GARTH, OF MILL HALL, PENNSYLVANIA.

Letters Patent No. 99,308, dated February 1, 1870; antedated December 1, 1869.

IMPROVEMENT IN STRAW-CUTTERS.

The Schedule referred to in these Letters Patent and making part of the same.

To whom it may concern:

Be it known that I, GEORGE S. GARTH, of Mill Hall, Clinton county, Pennsylvania, have invented a new and useful Improvement in Straw-Cutters; and I do hereby declare that the following is a full, clear, and exact description thereof, which will enable others skilled in the art to make and use the same, reference being had to the accompanying drawing, forming part of this specification.

This invention relates to improvements in straw-cutters, having for its object to provide an arrangement of the support of the fulcrum of the cutter-lever better adapted for holding the cutter firmly up to the steel or metal plate against which it cuts; also, for withstanding the wear; and the combination with the same of a friction or regulating-plate and thumb-screw, for holding the cutter firmly up to its position, but in such a manner as not to cause too much pressure of the knife against the fixed bed or cutter.

Figure 1 represents an end elevation of a straw-cutter arranged according to my improvement;

Figure 2 represents a top or plan view of the same;

Figure 3 represents an end elevation of the same, showing the friction-plate and adjusting-screw arranged on the side of the fulcrum-pin opposite to that in figs. 1 and 2; and

Figure 4 represents a section, taken on the line xx of fig. 3.

Similar letters of reference indicate corresponding parts.

The fulcrum and fulcrum-pin A are supported in a bracket, B, projecting from the front of the metallic plate C, which forms the open end of the cutter-box, and the bed against which the cutter works, the said bracket being provided with a part perpendicular to it, and parallel with the end of the said plate, projecting beyond the cutter-box at the rear side.

The cutter-lever E is provided with a circular disk, F, around the hole for the fulcrum-pin, and a projection, G, beyond.

From this circular disk, the said lever curves upward, at H, to rise above the bracket B, sufficiently to permit the knife to be moved downward below the bed I, for cutting.

The fulcrum-bolt support D is provided with a central stud, K, and a segment of an annular projecting

rib, L, the one working in a central socket, M, and the other in an annular groove, N, in the disk F of the lever E, by which the said lever is supported, so as to take all strain, except that required for holding them together laterally, off the fulcrum-pin, which is made angular in cross-section, and has an angular hole provided for it in the part D, to prevent it from turning with the lever.

Between the disk F of the lever, or the projection G thereof, and the projection O of the plate C, or the part D thereof, on either side of the said disk F, as found best, I place a friction-plate, P, for pressing against the disk F, or part G thereof, by a set-screw, Q, for holding the cutter close against the front face of the plate C rigidly, whereby it will be prevented from springing away when cutting, and yet will not be forced against it when not cutting, or when cutting small quantities, so as to turn the edge of the cutter, as will be the case when springs are used, for holding the cutter up to the plate, either in connection with plates P, or not.

When the friction-plate P is placed between the projections O and G, as represented in fig. 2, it may have projections, S, sliding into notches in the part O, to counteract the tendency of the plate to be moved by the oscillating disk or projection G of the lever; and, when the said friction-plate is placed as represented in fig. 4, the part D may be recessed to receive it, the said recess being made in such a manner that the pressure of the point of the thumb-screw holds the plate P firmly to its place.

Having thus described my invention, What I claim as new, and desire to secure by Letters Patent, is—

The combination, with the plate C and lever E, of the bracket B and parallel projection D, when the latter is provided with the circular stud K and curved projection L, and the lever E is provided with the socketed and grooved disk F, and both the disk and projection arranged for clamping together by the bolt A, substantially as specified.

G. S. GARTH.
